(57) **CLAIM**

The ornamental design for a pattern for an LED panel, as shown and described.

DESCRIPTION

FIG. 1 is a perspective view of a first embodiment of a pattern for an LED panel according to the design;

FIG. 2 is a perspective view of a second embodiment of a pattern for an LED panel according to the design;

FIG. 3 is a top view of the first embodiment of the pattern for an LED panel of FIG. 1 and of the second embodiment of the pattern for an LED panel of FIG. 2;

FIG. 4 is a front view of the second embodiment of the pattern for an LED panel of FIG. 2;

FIG. 5 is a left side view of the second embodiment of the pattern for an LED panel of FIG. 2;

FIG. 6 is a right side view of the second embodiment of the pattern for an LED panel of FIG. 2; and,

FIG. 7 is a rear view of the second embodiment of the pattern for an LED panel of FIG. 2.

The first embodiment of the pattern for an LED panel, shown in FIG. 1, is two-dimensional. Therefore, for this first embodiment, only the perspective view (FIG. 1) and the top view (FIG. 3) are provided. The remaining views are plain and unornamented and form no part of the claimed design. The second embodiment of the pattern for an LED panel, shown in FIGS. 2-7, is three-dimensional. The bottom view is omitted, because the bottom view is plain and unornamented and forms no part of the claimed design.

Throughout the figures, broken lines designate aspects of the pattern for an LED panel that form no part of the claimed design.
